UNITED STATES PATENT OFFICE.

WILLIAM F. SHOLL, OF HUBBELL, NEBRASKA.

COMBINATION SCREW-DRIVER AND TWEEZERS.

1,250,682.

Specification of Letters Patent. Patented Dec. 18, 1917.

Application filed March 7, 1917. Serial No. 153,026.

To all whom it may concern:

Be it known that I, WILLIAM F. SHOLL, a citizen of the United States, residing at Hubbell, in the county of Thayer and State of Nebraska, have invented certain new and useful Improvements in Combination Screw-Drivers and Tweezers, of which the following is a specification.

This invention relates to a combined screw driver and tweezers especially adapted for the handling of small screws such as are used by watch makers and repairers, but the device may be made in larger sizes and employed for use in holding screws of any size. It is, however, especially convenient in picking up and setting in place small screws not readily handled by the fingers.

The invention consists of the novel features of construction hereinafter described, pointed out in the claims and shown in the accompanying drawings in which:—

Figure 1 is a side elevation, showing the device in position for use.

Fig. 2 is a side elevation of the lower portion of the device, parts being shown in full lines in normal position and in dotted lines spread for use.

Fig. 3 is a section on the line 3—3 of Fig. 1.

Fig. 4 is a section on the line 4—4 of Fig. 1.

Fig. 5 is a section on the line 5—5 of Fig. 1.

In the drawings 1 represents a shank having a rotatable head 2. Mounted on the lower portion of the shank is a slidable sleeve 3 longitudinally slotted at 4, and a screw 5 extending through the slot into the shank limits sliding movement of the sleeve.

To opposite sides of the sleeve are secured spring tweezer members 6, which are adapted to embrace opposite sides of a screw driver 7 formed at the lower end of the shank, the device occupying a vertical position when in use.

Below the sleeve 3 is a second slidable sleeve 8 having a spiral slot 9 and a head 10, the head being in the form of an inverted cone and being provided with slots 11. Inwardly extending pins 12 are carried by the tweezers and engage the cone 10.

A finger 13 is secured to a sleeve 17 and the free end of the finger engages the spiral groove 9, of the sleeve 8.

To aid in holding the screws so that they

can be readily picked up by the device I employ a block 14 having tubular members 15, of assorted sizes on its upper face in which the screws 16 are held so that their heads can be readily grasped by the tweezers.

The cone 10 forms a spreader for the tweezers and the operation of the device is as follows: The sleeve 3 is moved downwardly and the pins 12 riding on the cone, the tweezers are spread apart, and when the pins have passed below the cone they spring together, gripping the head of the screw. After the screw has been placed in position, or has been removed as may be the case, the sleeve 3 is lifted upwardly. This brings the pins into engagement with the lower face of the spreader, lifting it, and during such lifting movement it is rotated by means of the finger 13 engaging the spiral groove 9.

Partial rotation of this sleeve and cone brings the notches 11 into alignment with the pins 12 and they pass through the notches, releasing the cone. Sleeve 8 then drops by gravity to normal position, thereby taking the notches out of alignment with the pins, and the device is ready to use on another screw.

For convenience of attachment I place 80 the finger 13 on a small sleeve 17 clamped to the shank by a screw 18, the sleeve 17 being stationary. But the said finger is to be considered as being carried by the shank, and I do not wish to be limited to any special 85 manner of securing it in place.

What I claim is:—

1. The combination with a screw driver, a slidable sleeve, tweezers carried thereby, a slidable spreading element adapted to rotate as it slides, pins carried by the tweezers adapted to engage said spreader, and means for rotating the spreader during its sliding movement, the spreader being notched, the notches coming into alignment with the pins 95 during rotation of the spreader, as and for the purpose set forth.

2. The combination with a screw driver, and tweezers for holding a screw, of a slidable sleeve supporting the tweezers, pins carried by the tweezers, a second slidable sleeve having a spiral slot and a notched cone, and a finger engaging the spiral slot, the pins riding over the cone on sliding

movement of the first mentioned sleeve and passing through the notches on opposite movement of the first mentioned sleeve.

3. In a device of the kind described, a pair of tweezers, a notched cone adapted to spread the tweezers, the tweezers having inwardly extending members adapted to ride over said cone, and the tweezers having lon-

gitudinal movement, and means for causing rotation of the cone on opposite movement of the tweezers thereby permitting said members to pass through said notches, the cone returning to normal position by gravity.

In testimony whereof I affix my signature.

WILLIAM F. SHOLL.
